2 Sheets-Sheet 2

Fig. 3.

UNITED STATES PATENT OFFICE.

VITAL PAQUIT, OF NEW YORK, N. Y.

ELECTRICAL APPARATUS.

Application filed August 17, 1920. Serial No. 404,117.

My present invention relates primarily to ignition apparatus especially for explosive motors, such as for aeroplanes and other vehicles, although some of the features are useful in connection with electrical generating and distributing systems and apparatus generally.

One of the objects of the invention is to provide ignition apparatus, the construction of which shall be simple and relatively inexpensive, the action of which shall, however, be thoroughly reliable.

Another object of the invention is to provide a novel ignition distributor that shall be of small dimensions and relatively inexpensive and in which each spark impulse is nevertheless, effectively conveyed toward the spark plug for which it is intended without likelihood of interference.

My invention is particularly concerned with a system including apparatus having preferably the general characteristics and external appearance of a magneto arranged with respect to the storage battery or other source of current usually provided on motor vehicles in such manner as to secure the combined advantages of battery ignition for low speeds and magneto ignition for high speeds.

According to a preferred construction the distributor and breaker are operated at equal speeds which for a four stroke cycle engine regardless of the number of cylinders is half engine speed, the rotors of the distributor and of the breaker being both preferably mounted upon the driving shaft.

Another feature of the invention in its preferred form is the provision of a distributor in which the terminals that lead to the spark plugs are arranged in two or more sets, the rotor having several contacts, one corresponding to each set. Preferably the terminals are arranged to provide sufficient space between them even with the use of a distributor of small diameter. In the preferred embodiment of the invention, the rotor comprises a cylinder of insulating material upon which are disposed rotor contacts spaced from each other both longitudinally and circumferentially, these contacts having electric terminals or brushes in their path for conveying the secondary current to the spark plugs.

In the accompanying drawings I have shown an illustrative application of my invention to a four cylinder engine, it being

understood, as will appear more fully below, that the invention is applicable to engines of any number of cylinders.

In the accompanying drawings in which is shown one of various possible embodiments of the several features of the invention:

Fig. 1 is a view in longitudinal section, parts being shown broken away, of a preferred form of ignition apparatus.

Fig. 2 is a transverse sectional view taken along the line 2—2 of Fig. 1, and;

Fig. 3 is a diagrammatic representation of preferred circuit connections, the distributor being diagrammatically shown in developed form.

This invention is an improvement upon that of my Patent No. 1,244,124, granted October 23, 1917.

Referring to the drawings I have shown a frame 1 having preferably the general external appearance of a magneto and comprising a base provided with ball or roller bearings 2 mounted in bearing holders A and B for a driving shaft 3 and a coil casting upper frame portion 4 which may be horse-shoe shaped between the ends 5 of which the induction coil 6 is supported by means not shown. The induction coil is of conventional construction comprising a magnetic core 7 encircled by a primary coil 8 and a secondary coil 9.

Upon the driving shaft 3 are preferably mounted both the distributor rotor 10 and the cam 11 of Fig. 3, said rotor being preferably of cylindrical form. The distributor in the embodiment shown for use with four-cylinder engines consists of a cylinder 12 of insulating material having a pair of electrical contacts 14—15 flush with the surface thereof. The contacts are rectangular in developed form as shown in Fig. 3 and constitute segments of rings or collars upon the rotor. The contacts are spaced from each other axially by a substantial distance 17 and are radially spaced by 90° or a quadrant as at 18.

Four contacting elements, preferably in the form of brushes 20—21—22—23 are provided, brushes 20 and 22 being in the path of contact 14 and brushes 22 and 23 in the path of contact 15. The four brushes preferably lie in a common plane axial of the rotor as best shown in Fig. 2, brushes 20—21 being in alignment along an element of the

cylindrical rotor and brushes 22 and 23 being similarly disposed upon the element diametrically opposite thereto.

It will be apparent that as the rotor is turned, for instance, in a counterclockwise direction from the position shown in Fig. 2, after contact 14 makes an electrical connection with brush 22 a rotation through a quadrant or 90° will bring contact 15 into registry with contact 23, a rotation through a second quadrant or 90° will bring contact 14 into registry with contact 20, a still further rotation of 90° will bring contact 15 into registry with contact 21, whereupon an additional rotation through a quadrant will bring contact 14 back into registry with contact 22 and the cycle will be repeated for each revolution of the rotor. The four contacts 20—21—22—23 are respectively connected to spark plugs 20'—21'—22' and 23' for the four cylinders of the engine, the leads from the distributor brushes extending through the side walls and the coil casing of the apparatus, connect terminals 40 located above the coil casing. It will thus be seen that as the rotor is turned through one revolution, current is conveyed to the spark plugs in succession at equal angular intervals.

The current is preferably conveyed to the rotor contacts 14 and 15 from a conducting ring 24 encircling cylinder 12 by means of conductors 25 and 26 preferably in the interior of the insulating cylinder, a brush 27 by preference contacting ring 24 to lead current thereto from the secondary 9 to which it is connected as shown at 41 in Fig. 3. Brush 27 is shown disposed at a cylinder element midway between brushes 20 and 22, although it may be placed in any position in contact with ring 24.

The breaker cam 11 which is mounted upon shaft 3 as above noted, by preference has four operating points or projections 27 which successively engage the wear piece 28 upon the breaker arm 29 (see Fig. 3). The breaker arm is mounted upon a plate 42 provided with a lug 33 through which timing is effected. A leaf spring 30 preferably urges the breaker arm 29 to press the contact 31 carried thereby against cooperator contact 32, the latter being mounted directly upon the plate 42.

As shown in Fig. 1 the breaker is preferably enclosed by the form of cover 35 commonly used on magnetos. A housing is provided, for instance, as at 36 in Fig. 1 for enclosing the usual form of condenser indicated diagrammatically at 37 in Fig. 2.

A resistance box 38 may be provided, if desired, to adapt the device for use with batteries of different voltages used by different makers and also to regulate the voltage of the primary and secondary circuits at will. A spark gap 39 may also be pro-

vided preferably in series between the secondary coil 9 and the brush 27 for intensifying the spark.

As shown in Fig. 3 the battery B is connected through the breaker contacts 32—31 to the primary coil 8, the condenser 37 bridging the contacts for the usual purpose, and the secondary coil 9 connects through the distributor to the spark plugs in the manner briefly indicated above and more fully set forth in the description of the operation below.

Assuming the ignition apparatus to be used on a four-stroke cycle engine regardless of the number of cylinders, the shaft 3 will be connected by any suitable form of power transmitting means to be driven at half engine speed. As the shaft turns, current will be delivered from the battery B through the contacts 31—32 while they are closed and through the primary coil 8 back to the battery. Magnetic flux will thereby be built up within core 7 and as soon as one cam projection causes the separation of contact 31 from contact 32, the circuit through coil 8 will be broken and the rapid breakdown of the flux will cause the induction of a high-tension current in coil 9. The parts as usual are so timed that the instant the primary circuit is opened, one of the contacts 14—15 of the rotor is in electrical connection with one of the terminals by means of a brush connected therewith and located on the side wall of the apparatus. Assuming contact 14, at the particular instant, to engage the brush 22, the high tension current will consequently pass from the secondary coil 9 through conductor 41 to the brush 27, through ring 24, and conductor 26 to contact 14 and by way of brush 22 to the corresponding spark plug 22' and back to the secondary coil. Immediately after the operation of the spark plug 22', the corresponding operating point of the cam will pass wearpiece 28, contacts 31—32 of the breaker will be closed by spring 30 and the flux will again build up in coil 8. When the next operating point of the cam reaches wearpiece 28, the breaker contact will open, and this concurrently with the engagement of contact 15 with brush 23 whereupon the spark plug 23' will be energized, and then in succession at intervals of rotations of 90° or of a quadrant the contact 14 will engage brush 20 and the contact 15 will engage brush 21, to operate the corresponding spark plugs.

As above indicated the principle of my invention is applicable to ignition apparatus for internal combustion engines having any number of cylinders. In every case I would arrange the contacts upon the distributor rotor with respect to the terminals in such manner that the current impulses would occur at equal angular intervals, each of the

spark plugs being energized once during each complete revolution of the rotor. Preferably I place two of the terminals 40 in the path of each rotor contact. For a six cylinder engine I would by preference arrange the six terminals, three upon each side of the rotor, three contacts being provided upon the rotor, one in the path of each pair of diametrically opposite contacting elements, the rotor contacts being spaced from each other circumferentially by angles of 120°. For an eight cylinder engine, the rotor would have four contacts, preferably at equal intervals longitudinally thereof and at intervals of 45° circumferentially thereof, there being four pairs of diametrically opposite contacting elements, one pair in the path of each of said contacts and for a twelve cylinder engine I would preferably 20 arrange six contacts upon the rotor at equal angular intervals of 30°, each contact being in the path of two diametrically opposite contacting elements.

In general the contacts are arranged upon 25 a helix on the cylindrical rotor and the contacting elements in a common plane axial of the rotor. Of course, the contacting elements might be arranged upon a helix and the contacts in a common plane upon the 30 rotor, this reversal producing results broadly equivalent to those specifically set forth.

It is also apparent that my invention might be embodied in constructions in which 35 three or more terminals have contacts in the path of each of the rotor contacts. In general, assuming the engine for which the apparatus is intended, to have $a \times b$ cylinders, contacts a in number might be provided upon the rotor, each of the contacts 40 having in its path terminals (b) in number; or contacts (b) in number might be provided upon the rotor, each having in its path terminals (a) in number.

The invention is clearly applicable also to 45 engines having an odd number of cylinders. Thus, in a nine cylinder engine, the terminals might be arranged in three sets of three each, the rotor carrying three contacts, one corresponding to each set of terminals.

50 Thus, my invention is embodied in a construction in which the terminals are distributed both about and along the length of a rotor, preferably in sets disposed in parallel planes. Although the number of terminals 55 of the various sets are preferably equal, this is not essential, any construction of the type set forth in which the circuits are successively closed at equal angular intervals during operation coming within the scope 60 of my invention.

It will be apparent that by arranging the contacts in the manner set forth, spacing them from each other both axially of the rotor and circumferentially thereof, I provide a 65 sufficient distance therebetween to prevent

interference between the circuits to the various spark plugs, where a distributor of a materially larger diameter would be required to avoid this difficulty should all of the contacts be placed in one and the same 70 plane, particularly for an engine having a large number of cylinders.

If desired, the coil casing together with the coil mounted therein may be made quick-detachable by the combined mechanical and 75 electrical plug and socket connections shown at 50.

Although the invention has its preferred application in a high tension ignition system, as set forth, it is apparent that it may be 80 applied to advantage also in a low tension system.

The same apparatus may be used upon a two-stroke cycle engine in which case it would, of course, be operated at engine 85 speed instead of at half-engine speed.

It will thus be seen that there is herein described apparatus in which the several features of this invention are embodied, and which apparatus in its action attains the 90 various objects of the invention and is well suited to meet the requirements of practical use.

As many changes could be made in the above construction and many apparently 95 widely different embodiments of this invention could be made without departing from the scope thereof, it is intended that all matter contained in the above description or shown in the accompanying drawings shall 100 be interpreted as illustrative and not in a limiting sense.

I claim:—

1. In a device of the class described, in combination, a frame having a base for motor attachment characterized by the appearance of a magneto in which said frame comprises a coil casing upper frame portion, the lower portion having a distributor housing closed by said upper frame portion, a coil 110 in said upper frame portion, a condenser adjacent one end of said upper frame portion, a circuit breaker adjacent one end of said lower portion, said circuit breaker and condenser being located on same vertical 115 and providing for short connection between each other, a rotor distributor of elongated form in said housing, a shaft with bearing arrangement in said lower portion to axially rotate the said distributor in a plane 120 parallel to the base of the frame, said shaft having both ends projecting outside of said frame, a cam with projections fixed to one end of said shaft and carried by said end within the enclosure of the circuit breaker, 125 a plurality of contacting elements disposed on and about said rotor distributor, terminals provided to said upper frame portion in line parallel to the axis of the distributor, and means adapted to convey the ignition 130

current from the distributor to said terminals.

2. A device of the class described having the general external appearance of a magneto and having the following characteristics, a coil casing upper frame portion, a condenser adjacent one end thereof, a coil in said casing, a brush connected with said coil and projecting from said casing, the lower portion of said device providing a housing closed by said upper frame portion, a circuit breaker adjacent one end of said lower portion, the said circuit breaker and condenser being located near each other on same vertical, a rotor distributor of elongated form in said housing, a rotary cam with projections to operate the circuit breaker, a common shaft for said cam and distributor, said shaft having a bearing arrangement provided to said lower portion to axially rotate said distributor in said housing in a plane parallel to the base of the device, said shaft having both ends projecting outside of said lower portion and having fixed to one end thereof a cam with projections carried by said end within the arrangement of the circuit breaker, the projections of the cam operating the circuit breaker in operative relation with respect to contacting elements substantially exposed on the surface of said distributor, the said contacting elements being in number half of the projections of the cam and contacting with a number of stationary elements double of the said contacts on the distributor, terminals for spark plugs connection provided to said upper frame portion in line parallel to the axis of the distributor, and means for conveying the ignition current from said stationary elements to said terminals.

3. The combination of a device of the class described, a frame having a base for motor attachment provided with a coil casing upper frame portion, a coil in said casing, a conductible element connected with said coil and projecting from said casing, a condenser adjacent one end of said upper portion, the lower portion of the device providing a distributor housing parallel to the base of said device, a circuit breaker adjacent one end of said lower portion, a cam with projections to operate said circuit breaker, a rotor distributor of elongated form in said housing, a common shaft for said distributor and cam, bearing arrangement for said shaft to axially rotate said distributor in said housing, said shaft having both ends projecting outside of said frame, one end serving for engine connection and the other end having fixed thereto the said cam carried within the circuit breaker arrangement, said distributor operating between the bearing arrangement and carrying a plurality of electrical contacts substantially exposed on its surface for co-

action with stationary contacting elements disposed to operate at consecutive intervals wherein a single contact of said distributor is in the path of two said stationary contacting elements diametrically opposed through the axis of the distributor, terminals provided to the upper portion of said frame in plane parallel to the axis of the distributor, and means to convey the ignition current from said stationary elements to said terminals.

4. In ignition system for high tension battery ignition for internal combustion engine, a unit having a coil casing upper frame portion, said portion being parallel to the axis of the distributor in said unit, a coil in said casing, said casing having adjacent one end thereof a condenser, terminals for spark plugs connection horizontally aligned above said casing, a rotor distributor of elongated form enclosed in the lower portion of the unit, a shaft with bearing arrangement located at both end walls of the lower portion to axially rotate said distributor in said portion, a circuit breaker adjacent one end of said lower portion, stationary contacting elements about said rotor distributor, means for conveying the ignition current from said stationary contacting elements to said terminals above the casing, and the various spark plugs circuit connected to said terminals being operated by means of a plurality of electrical contacts spaced on the circumference of the rotor distributor and within the said elongated form thereof.

5. The combination of a rotor distributor having a plurality of electrical contacts equi-spaced alongside its axis and cooperating with a plurality of stationary contacting elements adapted to operate the distribution of the ignition current by the combination of a frame enclosing said distributor in the lower portion thereof, a coil casing hermetically enclosing said distributor in said frame, a coil in said casing, breaker mechanism adjacent one end of the lower portion of said frame, means connecting said coil with said distributor, and means adapted to connect said contacting elements with the terminals provided upon said casing for spark plugs connections.

6. In ignition apparatus, a single unit having two portions, said portions being adapted to each other in a common plane, a coil in one of said portions, a condenser and circuit breaker externally located on said portions, a rotor distributor enclosed in one of said portions, said coil having its primary winding connected with a source of low tension current through said circuit breaker, the secondary of said coil having connected thereto an electrical element projecting from the portion having the coil to contact with said rotor distributor in the form de-

scribed, said distributor being of elongated form and carrying contacting elements moving in the path of a plurality of stationary elements longitudinally spaced about said 5 rotor distributor in a plane parallel to its axis and between the bearing arrangement of the shaft carrying the said distributor.

7. In ignition apparatus, in combination, a distributor housing having a base for motor attachment, a circuit breaker adjacent one end of said housing, a shaft having a bearing arrangement provided at both ends of said housing, demountable bearing holders for said bearing arrangement, one of said 10 bearings having a portion projecting outside of said housing, the projecting portion serving for the circuit breaker arrangement, a coil casing constituting an upper portion for said housing, a coil in said casing, said 15 coil and casing having a position parallel to the axis of the distributor, said distributor being of elongated form and axially rotated by said shaft in said distributor housing in combination with horizontally aligned 20 brushes within said housing.

8. In ignition apparatus, a distributor of elongated form enclosed in a frame having a base for motor attachment and having a bearing arrangement provided at both ends thereof, a shaft carrying said distributor between said bearing arrangement and axially rotating same within the enclosure of said frame, means projecting from said frame and impinging upon said distributor in a 30 plane parallel to its axis, terminals for spark 35

plugs connection connected with said means and aligned in a plane parallel to the axis of the distributor, a circuit breaker adjacent one end of said frame and having a bearing arrangement of the distributor therebetween.

9. A device of the class described comprising two portions forming a unit, said unit having a base for motor attachment parallel to the axis of the distributor thereof, said distributor being of elongated form and located in the portion having the base, a circuit breaker mechanism mounted adjacent one end of said unit, a condenser externally located near said circuit breaker mechanism, a common shaft for said distributor and circuit breaker, a plurality of horizontally aligned brushes within the lower portion of said unit which are removable therefrom as shown in the accompanying drawings, 50 a coil in the upper portion of said unit and means to connect said coil with said distributor.

10. In ignition apparatus, a single unit comprising a coil casing upper frame portion thereof, a coil in said casing, and an electrical element connected with said coil and projecting from said casing to connect the distributor of said unit with said coil in the form described.

Signed at New York city in the county of New York and State of New York this 12th day of August A. D. 1920.

VITAL PAQUIT.
